UNITED STATES PATENT OFFICE.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

APPARATUS FOR DISTILLING HYDROCARBONS.

Application filed June 3, 1922. Serial No. 565,635.

To all whom it may concern:

Be it known that I, FRANK E. WELLMAN, citizen of the United States, residing at Kansas City, in the county of Wyandotte 5 and State of Kansas, have invented certain new and useful Improvements in Apparatus for Distilling Hydrocarbons, of which the following is a specification, reference being had therein to the accompanying drawing.

10 My invention relates to systems for the treatment of hydrocarbon oils for the production of gasoline. It has for its objects the improvement in apparatus for fractionating distilled products and re-treating the 15 heavier fractions thereof; the provision of means for accurately and uniformly controlling the intermediate heating of the distilled products prior to re-treatment; and the provision of means to increase the yield of gasoline 20 line while maintaining the required boiling points of the fractions finally condensed.

I attain my objects by providing a cracking still, a vapor line and fractionator therefor, a supplemental still into which the fractionator drains, a supplemental fractionator 25 therefor, a condenser, vapor line connections from both said fractionators to said condenser, and a pressure controlling valve in said vapor line to maintain uniform pressure on all parts of the system except the 30 condenser, but permitting condensation at a substantially lower pressure therein.

My invention is illustrated in the accompanying drawing, in which the figure is a 35 diagram of the system without mechanical detail.

In the drawing, 1 indicates the cracking still, 2 the vapor line therefrom to the fractionator 3 having a feed pipe 8, a vapor line 40 10, and a down pipe 4 into the supplemental still 5, which is connected by vapor line 9 to a supplemental fractionator 6 also connected to the vapor line 10 and thence to a pipe line 12 leading to the condenser 13 from 45 which suitable connection is effected to the storage tank 14. Stills 1 and 5 are heated by furnaces 1^a and 5^a, respectively.

In operation, the cracking still being filled 50 with hydrocarbon oil to the level marked 15, is heated to approximately 750° F., whereupon vapors pass through the line 2 to the fractionator 3, wherein cooling and condensation of the heavier fractions take place,

the lighter vapors passing over and into pipe line 10. The heavy condensate is thrown 55 down and drains through pipe 4 into the supplemental still 5, which is filled to common liquid level 15, maintained through the pipe 7. Heat is applied to the supplemental still 5 and the oil therein is redistilled at 60 approximately 550° F., the vapors produced passing through pipe 9 and fractionator 6 to pipe 10. These vapors are released 65 through valve 11 and pass through pipe line 12 to the condenser, where they are all condensed under pressure of twenty pounds or less. The process is rendered continuous by supplying fresh oil through supply pipe 8, as the level 15 is lowered by withdrawals.

The advantages attained by the introduction 70 of supplemental heating thus described, will be obvious to those skilled in the art. In the previous systems referred to, in which simultaneous cooling and refluxing are carried on, rising vapors are constantly carrying 75 and giving up heat to the condensed and condensing material already in the run-back or fractionator, so that both cooling and heating effects are produced, without control of the resultant temperature to which the reflux is raised on its journey back to the cracking still. The reflux material merely 80 absorbs whatever heat is communicated to it in amount depending upon its own weight in proportion to that of the ascending vapors 85 and the difference in the temperatures.

I claim:

A system for the treatment of hydrocarbon oil comprising a cracking still, a fractionator, a vapor line therebetween, a supplemental still, a down pipe from said fractionator to said supplemental still, a second fractionator extending alongside said first fractionator and connected to said supplemental still, a condenser, vapor line connections from both said fractionators to said condenser, a return pipe from the supplemental still to the cracking still, and a feed pipe connected to the first named fractionator for introducing fresh oil into the system through said fractionator and said supplemental still.

In testimony whereof I hereunto affix my signature.

FRANK E. WELLMAN.
